TELEVISION RECEIVER CABINET

David Painter, Evanston, Ill., assignor to Aveo Manufacturing Corporation, Cincinnati, Ohio, a corporation of Delaware

Application December 14, 1949, Serial No. 6,624

Term of patent 3½ years

(Cl. D56—4)

To all whom it may concern:

Be it known that I, David Painter, a citizen of the United States, residing at Evanston, Illinois, in the county of Cook, have invented a new, original, and ornamental Design for a Television Receiver Cabinet, of which the following is a specification, reference being had to the accompanying drawing, forming a part thereof.

The single figure is a perspective view of the front, top and side panels of a television receiver cabinet, showing my new design.

The opposite side not shown and the back of the television receiver cabinet are plain.

I claim:

The ornamental design for a television receiver cabinet, as shown and described.

DAVID PAINTER.
